UNITED STATES PATENT OFFICE.

JOSEPH E. DALLEN, OF MILTONVALE, KANSAS.

SNOW-CUTTER.

1,235,445.

Specification of Letters Patent. Patented July 31, 1917.

Application filed November 24, 1916. Serial No. 133,207.

To all whom it may concern:

Be it known that I, JOSEPH E. DALLEN, a citizen of the United States, residing at Miltonvale, in the county of Cloud and

5 State of Kansas, have invented certain new and useful Improvements in Snow-Cutters; and I do hereby declare the following to be a full, clear, and exact description of the invention, such as will enable others skilled in 10 the art to which it appertains to make and use the same.

This invention relates to a snow cutter and has for one of its objects, the provision of a device of this character, especially 15 adapted to be attached to the cow catcher or fender of a locomotive for the purpose of cutting through a snow drift or the like.

Another object of this invention is to provide a cutting disk rotatably supported on 20 the cow catcher for the purpose of cutting a passage through a snow drift or the like so that the apex portion of the cow catcher or fender of the usual type may have a path drift or the like so that the snow drift 25 or the like will be readily parted and pushed to each side of the track by the cow catcher or fender.

A further object of this invention is to provide an arm bolted to the locomotive and 30 extending forwardly of the cow catcher or fender and having its forward end bifurcated to receive the rotary cutter so that the cutter will be forced through the snow drift or the like.

35 A still further object of this invention is to provide a snow cutter of the above stated character, which shall be simple, durable and efficient, and which may be manufactured and sold at a comparatively low 40 cost.

With these and other objects in view, as will become more apparent as the description proceeds, the invention consists in certain novel features of construction, combination and arrangement of parts as will 45 be hereinafter more fully described and claimed.

For a complete understanding of my invention, reference will be had to the following description and accompanying drawings, in which:

Figure 1 is a side elevation of a snow cutter constructed in accordance with my invention, illustrating it applied to a locomotive,

Fig. 2 is a top plan view of the same, Fig. 3 is a detail sectional view illustrating the means of journaling the disk or cutter.

Referring in detail to the drawings, the 60 numeral 1 indicates a locomotive having the usual cow catcher or fender 2 secured to the forward end thereof and to which my invention is applied.

An arm 3 has one end thereof bolted or 65 otherwise secured to the cross piece of the cow catcher or fender 2 and has its other end curved downwardly and bifurcated to form a pair of relatively spaced arms 4 which are apertured and internally screw-threaded to receive external screwthreaded bearings 5 in which are journaled hubs 6. The hubs 6 are bolted or otherwise secured to a circular disk 7 which increases in thickness from its periphery in the direction of 70 the point of attachment of the hubs thereto.

Secured to the arm 3 upon each side thereof are rearwardly and downwardly extending braces 8 which are in turn bolted or otherwise secured to the fender or cow 80 catcher 2 to prevent the arm 3 from bending or twisting when in operation. To further assure the arm 3 and the pair of relatively spaced arms 4 from bending, a pair of braces 9 are bolted to the pair of relatively spaced arms 4 and to the cow catcher or fender 2. 85

In operation, when the locomotive 1 approaches a snow drift, it will be first engaged by the disk cutter 7 whereby a channel or passage is made within the snow drift so that the cow catcher or fender 2 may readily pass through the snow drift causing portions of the snow drift to pass upon each side of the locomotive, thus obviating the necessity of taking out or clearing tracks of snow drifts which now is the usual practice. 90

The bearings 5 are provided with apertures 10 communicating with the interior 100 thereof and having grease cups 11 threaded therein for supplying the hubs 6 with lubricants. The bearings 5 being threaded into the arms 4 provide means whereby the wear of the hubs within the cap may be readily compensated. 105

While I have shown and described the preferred embodiment of my invention, it will be understood that minor changes in construction, combination and arrangement 110

of parts may be made without departing from the spirit and scope of the invention as claimed.

Having thus described my invention, what I claim is:

1. In combination with a locomotive including a fender, of an arm secured to the fender and extending forwardly thereof, a vertical disk journaled to the forward end of the arm for cutting a passage through a snow drift.

2. In combination with a locomotive in-

cluding a fender, of an arm secured to the fender and extending forwardly thereof, said arm having its forward end bifurcated to form a pair of relatively spaced arms, said relatively spaced arms having openings internally screwthreaded, adjustable bearings threaded in said openings, hubs journaled in said bearings, and a disk secured centrally to the hubs for cutting a passage through a snow drift.

In testimony whereof I affix my signature.

JOSEPH E. DALLEN.
